UNITED STATES PATENT OFFICE.

WILLIAM W. DEAN, OF CHICAGO, ILLINOIS, ASSIGNOR TO KELLOGG SWITCH-BOARD AND SUPPLY COMPANY, OF CHICAGO, ILLINOIS, A CORPORATION OF ILLINOIS.

TELEPHONE TRUNKING SYSTEM.

No. 842,178.

Specification of Letters Patent.

Patented Jan. 29, 1907.

Application filed January 22, 1903. Serial No. 140,166.

To all whom it may concern:

Be it known that I, WILLIAM W. DEAN, a citizen of the United States, residing at Chicago, in the county of Cook and State of Illinois, have invented new and useful Improvements in Telephone Trunking Systems, of which the following is a specification.

In an application filed by me June 28, 1902, Serial No. 113,581, I have shown and described a telephone trunking system in which a relay that is actuated over a portion of the talking-circuit when the incoming end of the trunk is connected with the called line serves to disconnect the test-relay and place the tip trunk-cord in condition for conversation, to suitably control the circuits through the ringing-signal and locking-relay, and to open and close the local circuit of the calling and disconnecting signal. In the present application the relay that is actuated over the talking-circuit in the manner above explained serves to control a locking-circuit of an auxiliary relay which takes the place of the first-named relay in the system above described and which is initially operated over a local circuit controlled by the ringing-key.

My invention is illustrated in the accompanying drawing, in which the figure represents a diagram of a trunk-circuit extending between two central offices, together with radiating lines from each of the offices.

L indicates one of the radiating telephone-lines from the outgoing central office or A office, which lines are preferably of the two-wire or Dunbar type. At the central office of the A exchange a cord-circuit is shown of the usual type suitable for connecting the subscribers' lines together for conversation, while a trunk-line is shown extending from the A office to the B office, where it terminates in the usual flexible cord and plug. At the incoming or B office telephone-lines, such as L², and which are also of the two-wire type center and are provided with suitable connection-terminals or spring-jacks to enable the subscribers to be connected together for conversation. The trunk-circuits terminating at this office are provided with ringing-signals to indicate that the called subscriber has not yet responded and with disconnecting-signals which show when the cord-circuit at the A office has been disconnected from the trunk. Suitable means are provided at

this end of the trunk to ring the wanted subscriber and to test the condition of his line to determine its idle or busy condition.

The subscriber located upon the line L desiring a connection with another subscriber whose line terminates at the B office takes up his receiver and thereby closes a path for current over the telephone-line from the battery B', thus operating the line-relay R² of the line and lighting the line-lamp S. Upon observing this signal the A operator inserts the answering-plug P of her cord-circuit in the answering-jack J of the calling-line, thereby operating the cut-off relay R of the line L to render the line-signal inoperative and to connect the spring-jack with the external line-circuit.

By means of the listening-key k the operator is enabled to connect her head-telephone with the opposite end of the cord-circuit to receive the order from the calling subscriber, her transmitter 28 being at this time energized by current from the central battery B². The presence of current in the battery B' over both sides of the cord-circuit and the telephone-lines operates both supervisory relays r² and r³, and the supervisory signal remains inert.

Upon learning that a subscriber in the exchange B is wanted the order-key k² is depressed to connect her head-set with the order wire or circuit 33, extending to the other exchange, where it is joined to the B operator's instrument. In response to the order for connection the B operator nominates the trunk to be used and immediately proceeds to test the condition of the wanted line by means of the trunk-plug P³, while simultaneously the A operator completes the connection at her office by inserting the calling-plug P² of her cord-circuit in one of the jacks of the trunk. If the tested line is busy, a path for testing current is provided over the tip-strand t² of the trunk-cord and through the spring 42 of the auxiliary relay r¹⁸, its normal contact, and the conductor 43, leading to the test-relay of high resistance and high impedance and thence to ground. The operation of this relay causes a click in the operator's receiver. Upon finding the line idle the trunk-plug P³ is inserted and the ringing-key k⁴ k⁴ operated to call the wanted subscriber. It will be noted that the call-bell 6 at the sub-

station upon the line L^2 is connected with the tip-conductor 2 thereof when a receiver is upon the hook-switch and since the calling-generator 60 is connected between ground 5 and the tip side of the trunk ringing-current is suitably sent out over the tip side of the line to actuate said call-bell. At the same time the cut-off relay R of the line is actuated by current over the sleeve-cord s^3 of the trunk 10 by current from the battery B^3 , and since this circuit is not open during ringing the cut-off relay remains actuated. The depression of the sleeve-spring of the ringing-key k^4 completes in the first instance the circuit of the auxiliary relay r^{13} from the battery B^3 , conductor 15 40, through the said relay, and thence by conductor 40^a , to the said spring k^4 and to ground. As soon as this relay is operated it completes a locking-circuit for itself through 20 the branch conductor 40^b , the forward contact and spring 40^c of said relay, conductor 40^d , the forward contact and spring of sleeve-relay r^9 , and thence to ground. This relay r^{13} therefore remains actuated as long as said 25 sleeve-relay r^9 is energized.

Upon the connection of the cord-circuit at the A office with the outgoing end of the trunk a path for current from the battery B^2 is provided over the sleeve-strand s^2 of the cord-circuit 30 through the supervisory relay r^5 and thence over the sleeve strand or conductor of the trunk-circuit, through the high-resistance trunk-relay r^7 at the incoming office, and thence back to the A office over the tip side 35 of the trunk and through the tip-strand of the cord-circuit to the other side of the battery B^2 . It will be understood that the initial operation of the supervisory relay r^5 , which accomplishes the completion of the tip-cord strand, is secured through the grounded retardation-coil 34. The high resistance of the trunk-relay r^7 prevents the operation of the tip supervisory relay r^4 in the A cord-circuit, so that the supervisory lamp S^3 is lighted 40 to indicate to the A operator that the called subscriber has not yet responded. Likewise at the incoming end of the trunk the ringing-lamp S^4 is now lighted by current from the battery B^3 over conductor 40, point 45 54, through the lamp S^4 , the normal contact and spring of locking-relay r^{11} , conductor 55^a forward contact and spring 51 of relay r^{13} to ground.

When the subscriber answers his call, current from the battery B^3 flows over the metallic line to the substation and back to the central office through the tip-relay r^8 , which is actuated to close the short-circuit through the spring 37 and forward contact of the said 55 high-resistance trunk-relay r^7 . The said resistance being removed from the path for current over the trunk permits the tip supervisory relay r^4 in the A cord-circuit to operate and opens the circuit of the supervisory lamp S^3 , which is rendered inert to indicate to the A 60

operator that the called subscriber has responded. Similarly, the spring 57 closes upon its forward contact the circuit of the locking-relay r^{11} , which is completed from the battery-lead 40 through the said relay, conductor 70 56, forward contact, and spring 57, conductor 57^a , conductor 55^a , and spring 51 to ground. The locking-relay is therefore actuated and opens the circuit of the ringing-lamp S^4 and thereby extinguishing the same 75 and indicating to the B operator also that the called subscriber has responded. The path for current through relay r^{11} is now also completed through its spring and forward contact, whereby although the tip-relay r^8 is de-energized when the called subscriber hangs up his telephone the said locking-relay remains actuated and the ringing-lamp is prevented from operation during the connection. 80

During conversation the battery B' at the 85 A office is furnishing current to the line L for transmission, while the battery B^3 at the other office is furnishing current for the line L^2 for transmission. At the termination of the conversation the subscribers return their receivers to the hooks, with the result that the supervisory signal S^2 is directly operated at the A office, and the tip-relay r^8 at the B office is deenergized and the resistance of relay r^7 again introduced into the trunk-circuit, 90 thereby deenergizing tip-relay r^4 in the A cord and lighting the supervisory signal S^3 . The A operator seeing the supervisory signals associated with her cord exposed takes down the connection and restores the parts 100 at her office to normal position. The withdrawing of the cord-circuit at the outgoing end of the trunk deenergizes the trunk-relay at the incoming end, and since the tip-relay r^8 has been already deenergized a path for 105 current from the battery-lead 47 is provided through the disconnect-pilot relay r^{12} and signal S^5 over conductor 53, spring, and back contact of trunk-relay r^7 , conductor 52, back contact, and spring 57 of relay r^8 , conductor 110 57 a , conductor 55^a , and spring 51 to ground. This disconnect-signal, as well as the pilot-signal S^6 , is lighted, thus indicating to the B operator that the conversation has terminated, whereupon she withdraws the trunk- 115 plug and restores all parts to normal condition.

In case it be desired to dispense with the order-circuit the A operator may test the condition of the trunks before her upon receiving an order for a connection and upon finding an idle one insert the calling-plug P^2 . This operates the trunk-relay r^7 , which closed through its forward contact, conductor 59, and spring 51 of relay r^{13} the local circuit of 120 lamp S^5 , which now serves as a calling-signal. In response to this signal the B operator connects her telephone with a cord-circuit by the listening-key k^6 and receives the order 125 from the A operator. The subsequent steps 130

of establishing and clearing out the connection is the same as previously stated and is unnecessary to be repeated here. It should be mentioned, however, that the insertion of 5 the trunk-plug into the jack of the called line and the operation of the ringing-key serves to operate the auxiliary relay r^3 , to thereby open the circuit of said calling-signal through its spring 51 and back contact; also, that the 10 condenser c^8 (shown in dotted lines) permits conversation between the operators without hindrance from the trunk-relay r^7 .

Although the call-bell at the substation upon line L^2 is legged to ground from the tip side, it will be understood that the plug may be used for metallic calling or that a party-line may be provided in which the call-bells are legged to ground from the opposite line conductors. This system is shown in my 15 application, Serial No. 142,292, filed February 7, 1903, in which an auxiliary relay is shown in connection with a cord-circuit adapted for directly connecting lines together for conversation. This calling-signal of 20 course operates as a guard-signal when the order-circuit is used for communicating between the operators in making connections, for the reason that should the order be misunderstood by the A operator and the cord- 25 circuit connected by her with an idle trunk the said signal will be operated to notify the B operator that an error had been made. Likewise inserting the plug of the wrong trunk in the jack of the called subscriber by 30 the B operator results in operating said guard-signal to again notify the B operator that a mistake has been made. The said signal S^5 therefore acts as a guard-signal under this 35 method of establishing connections between 40 subscribers at the different exchanges.

I claim—

1. The combination with a trunk-line, of a 45 cord-circuit to connect with its outgoing end and a called-subscriber's line to connect with its incoming end, a retardation-coil legged to ground from one side of the talking-circuit established by the connection of the cord with the trunk, a supervisory signal associated with the cord-circuit and placed in operative condition when the cord is connected 50 with the trunk, a trunk-relay at the other end of the trunk actuated when the cord is first connected with the trunk by current over one side of the same with suitable return, a trunk-signal actuated by the energization of said relay, a second relay associated with the incoming end of the trunk, said relay being actuated by current flowing over a local circuit closed by the ringing-key when 55 the operator is calling the wanted subscriber, said second relay when operated being adapted to extinguish said trunk-signal, a locking-circuit for said latter relay, and a third relay energized during connection of the trunk and 60 line to control said locking-circuit, and

means under the control of the called subscriber for extinguishing said supervisory signal, substantially as described.

2. The combination with a trunk-line, of a 70 cord-circuit to connect with its outgoing end and a called-subscriber's line with which its incoming end is connected, a ringing-signal for the incoming end of the trunk, a source of current at said end to actuate said signal and to energize the transmitter of the called-subscriber's line, a relay actuated over a local circuit closed by the actuation of the ringing-key when the operator is calling the wanted subscriber, said relay serving to direct current through said signal to operate 80 the same when the subscriber has been called but before his response, a second relay adapted to deprive said relay of operating-current when the subscriber responds, and a locking-relay for locking out said signal during the remainder of the connection, substantially as described.

3. The combination with a trunk-line, of a 85 cord-circuit to connect with its outgoing end and a called-subscribers's line with which its 90 incoming end is connected, a disconnect-signal for said incoming end, a source of current for said signal and adapted to energize the transmitter of the called-subscriber's line, means operated by current flowing over a 95 local circuit closed by the ringing-key when the operator is calling the wanted subscriber, to place said signal in condition to operate, and further means controlled by the connection of said cord-circuit with the trunk for 100 rendering said signal inoperative, substantially as described.

4. The combination with a trunk-line, of a 105 cord-circuit to connect with its outgoing end and a called-subscriber's line with which its incoming end is adapted to connect, a signal 110 associated with said incoming end, a source of current for said signal and adapted to energize the transmitter of the called-subscriber's line, a relay also at the incoming end adapted to be operated by current sent over the trunk-circuit, a second relay at said incoming end operated by current flowing over a local circuit independent of the connecting-plug and closed by the operation of the ringing-key in calling the wanted subscriber, said relays jointly controlling said signal so as to operate the same to give a guard indication when the cord-circuit is connected 115 with the trunk-circuit and the trunk-circuit is disconnected from said line, or to place said signal in condition to operate so as to give a disconnect indication when the cord-circuit is disconnected from the trunk and the trunk is connected with said line, substantially as described.

5. The combination with a trunk-line, of a 120 cord-circuit to connect with its outgoing end and a called-subscriber's line with which its incoming end is adapted to connect, a guard- 125

- signal for the incoming end of the trunk, means to actuate said signal by current sent over the trunk when the cord-circuit is connected with the trunk, and further means 5 actuated by current over a local circuit independent of the connecting-plug and closed when a called subscriber is rung for rendering said signal inert, substantially as described.
6. The combination with a trunk-line and 10 a called-subscriber's line, of a relay associated with said trunk-line and adapted to be operated over a local circuit independent of the connecting-plug and closed by the operator in ringing the called subscriber, a second relay adapted to open said local circuit, a testing-circuit completed over one strand of the trunk cord-circuit and including the normal contacts of said relay, an operator's telephone-circuit connected with said testing- 15 circuit and provided with order-wire leads whereby the operator may receive a test-signal without the use of a manual switch, and whereby the testing-circuit is disconnected by the ringing of the called subscriber, 20 substantially as described.
7. The combination with a trunk-line, of a cord-circuit to connect with its outgoing end and a called-subscriber's line with which its incoming end is to connect, of signaling apparatus associated with the incoming end of the 25 trunk, a relay actuated over a local circuit independent of the connecting-plug and closed in ringing the wanted subscriber, a second relay adapted to open said local circuit, a testing-circuit completed through the 30 normal contacts of said relay, and means for placing said signaling apparatus in condition to operate and for disconnecting the testing-circuit when the said relay is actuated, 35 substantially as described.
8. The combination with a telephone trunk-circuit extending between different switchboard-sections and adapted to connect telephone-lines together for conversation, of two signals associated with the incoming end of said trunk-circuit and adapted by their condition to impart information to facilitate the utility of the trunk-circuit, a 45 source of direct current associated with the trunk-circuit, a relay associated with said source and controlling contacts in the circuit of each of said signals, the circuit of said relay

being first controlled by means independent of the talking-circuit and thereafter by current flowing over a portion of the talking- 55 circuit, substantially as described.

9. The combination with a trunk-circuit, of a cord-circuit adapted to be connected therewith at its outgoing end, and a telephone-line with which the incoming end is 60 adapted to connect, a signal associated with the incoming end of the trunk, a relay to control the circuit of said signal energized by the actuation of the ringing-key in calling the wanted subscriber, a second relay actuated 65 when the connection is established with the called telephone-line to place said first relay in condition to actuate, a third relay actuated upon the response of the calling subscriber to efface said signal, locking-circuits 70 for said first and third relays, and contacts of said second relay controlling said locking-circuits, whereby the relays will all be deenergized when the trunk is removed from its connection with the line, substantially as de- 75 scribed.

10. In a telephone system, the combination with a trunk-line, of a cord-circuit adapted to be connected with said line at its outgoing end, and a telephone-line with 80 which the incoming end of said trunk may be connected, a signal for the incoming end of the trunk, a relay actuated over a local circuit including contacts of the ringing-key to display said signal, and a relay actuated over 85 a portion of the talking-circuit when the connection is established with the called line to place said first relay in condition to operate, a third relay actuated when the called subscriber answers his call to efface said signal, a 90 locking-circuit for said first and third relays, the locking-circuit of the third relay being controlled by contacts of said first relay, and the locking-circuit of said first relay being controlled by contacts of said second relay, 95 substantially as described.

Signed by me at Chicago, county of Cook, State of Illinois, this 17th day of January, 1903.

WILLIAM W. DEAN.
